Primary Examiner — Omeed Agilee*(74) Attorney, Agent, or Firm* — Andrus Intellectual Property Law, LLP(57) **CLAIM**

The ornamental design for a pipette tip dispenser, as shown and described.

DESCRIPTION

FIG. 1 is a front perspective view of a pipette tip dispenser showing our new design;

FIG. 2 is a rear perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed lines in the drawings depict portions of the pipette tip dispenser that form no part of the claimed design. The dot-dash lines depict the boundaries of the claim and form no part thereof.
